UNITED STATES PATENT OFFICE.

ANTON C. EGGERS, OF NEW YORK, N. Y., ASSIGNOR TO THE GOODYEAR'S
INDIA RUBBER GLOVE MANUFACTURING COMPANY, OF SAME PLACE.

DESIGN FOR A WATER-BOTTLE.

SPECIFICATION forming part of Design No. 33,102, dated August 21, 1900.

Application filed June 2, 1900. Serial No. 18,904. Term of patent 7 years.

To all whom it may concern:

Be it known that I, ANTON C. EGGERS, a citizen of the United States, residing at New York, in the borough of Brooklyn and State of New York, have invented and produced a new and original Design for Water-Bottles, of which the following is a specification, reference being had to the accompanying drawings, forming a part thereof.

10 Figure 1 is a side elevation of the water-bottle, and Fig. 2 is a central transverse section thereof.

The material features of my design for a water-bottle are a flat circular body having a 15 surrounding edge with a semicircular contour from side to side of the said body, the ends of which edge merge into a spreading or frusto-conical portion from which extends an oblong portion, the side edges of which are 20 substantially parallel with the vertical axis of the said body.

A indicates the flat body of circular shape, having a surrounding edge a of semicircular shape from side to side of the body, $a' a'$ being the opposite sides of the body.

25

B indicates the frusto-conical or spreading portion, from which extends the oblong portion or elongation C, diametrically opposite which is a ring-shaped portion D.

30

The body A has a marginal scalloped ornamentation a^2 and the frusto-conical portion B scalloped ornamentations $b b'$.

35

What I claim is—

The design for a water-bottle, as shown and described.

In testimony that I claim the foregoing as my invention I have signed my name in presence of two subscribing witnesses.

ANTON C. EGGERS.
